BRUNO J. CLOUSE, OF BAKERSFIELD, CALIFORNIA

OVERSHOT

Application filed April 28, 1931. Serial No. 533,499.

My invention relates generally to overshots of the character employed in drilling operations at oil and water wells for the recovery of pipe and casing which has broken off in the hole.

It is a purpose of my invention to provide a device which in its association with a conventional form of overshot, enables the latter to be readily applied to a pipe which has broken off in the hole and become bent so as to be eccentrically disposed to such extent that it would not be possible to successfully fish for the pipe with the overshot alone, to the end of avoiding loss of the pipe as well as abandonment of the hole should it be impossible to drill past the pipe.

It is a further purpose of my invention to provide a device of the above described character embodying a guiding or directing member which during lowering of the overshot into the hole occupies a position wherein it will not interfere with the lowering operation, and is preferably although not necessarily moved to a working position for engagement with the pipe to be fished, by utilizing the pressure of the usual circulating fluid employed during drilling operations.

I will describe only one form of overshot embodying my invention, and will then point out the novel features thereof in claims.

In the accompanying drawings:

Figure 1 is a view showing in vertical longitudinal section one form of guiding device embodying my invention associated with a conventional overshot.

Figure 2 is a vertical longitudinal sectional view taken on the line 2—2 of Figure 1 and looking in the direction of the arrows.

Figure 3 is a horizontal sectional view taken on the line 3—3 of Figure 1 and looking in the direction of the arrows.

Figures 4, 5, and 6 are views similar to Figure 1 and illustrating various positions occupied by the device during the fishing operation.

Referring specifically to the drawings in which similar reference characters designate similar parts in each of the several views, my invention in its present embodiment is shown associated with a conventional overshot hav-

ing the usual belled nipple or bowl 10 attached to a hollow head 11 containing a circular series of spring slips 12 and connected by means of a length of casing 13 to a drill pipe (not shown) for lowering of the overshot over a pipe or casing which has broken off in a bore hole.

My invention in the present instance comprises a guiding member G in the form of a rigid arm of metal pivotally mounted adjacent one end on a pin 14 journaled in bearings 15 secured by bolts 16 in a hollow cylindrical piston 17 slidably mounted in the casing 13 of the overshot. The member projects freely through a slot 18 in the piston in order to permit rocking movement of the member about the axis of the pin; and it will be understood that the pin and piston broadly constitute means for mounting the member in the overshot for movement lengthwise or axially thereof and pivotal movement about the axis of the pin radially with respect to the overshot to occupy either the inactive position shown in Figure 1 or the active position shown in Figure 4.

The piston 17 is adapted to rest upon the slips 12 of the overshot to definitely limit outward movement of the member G axially of the overshot; and in this extreme axial position of the member, its outer or forward extremity 19 is disposed in advance of the forward edge of the bowl 10.

Under the action of gravity, the member G normally swings about the axis of the pin 14 to its inactive position wherein it is disposed within a circle defined by the outside diameter of the bowl 10 so as not to interfere with lowering movement of the overshot. In the present instance the member is adapted to be swung to its active position by fluid pressure responsive means; and to this end a flexible extension or bar 20 is secured to the pivoted end of the member by bolts 21 so as to be disposed in the piston 17. To the free upper end of the extension is secured by bolts 22 an abutment 23 in the form of a metal plate bent to provide diverging wings 24 which determine the inactive position of the member by resting against the inner wall of the piston as shown in Figure 3.

A length of pipe 25 is supported by the piston with one end in communication with the interior of the overshot casing 13 above the piston 17 and its other end directed towards the abutment 23 so that upon the pumping of the usual circulating fluid into the casing 13, the fluid will be forced through the pipe and will impinge against the abutment to thereby exert sufficient force against the latter to rock the guiding member about the pin 14 to its active position wherein its forward extremity is disposed beyond the diameter of the bowl 10 for engagement with the upper end of a drill pipe or casing P which has broken off in the hole and is bent so as to be off center in the hole or crowded against the wall of the latter and possibly partially imbedded in the formation.

The forward extremity of the guiding member is beveled as indicated at 26 so as to enable the member to enter the upper end of a drill pipe, and is also provided with a shoulder 27 adapted to abut the upper edge of the pipe to limit the extent to which the member can enter the pipe. Inclined surfaces 28 and 29 on the forward extremity of the member are adapted to be engaged by the overshot bowl to cam the member radially inward about the pin 14 during the lowering operation for a purpose to be later described.

In order to seal the piston against the escape of fluid pressure around it, the upper end of the piston is provided with a packing 30 so that upon the pumping of circulating fluid into the overshot casing 13 to force the guiding member to its active position, the fluid pressure will also be exerted upon the piston to positively move it to and maintain it in engagement with the slips 12 wherein the guiding member is disposed in its extreme axial position shown in Figures 1 and 4.

Ports 31 in the lower end of the piston, and an upwardly opening check valve 32 in the upper end of the piston permit the passage of fluid through the piston so that lowering movement of the overshot will be unrestricted by the fluid as will be understood. An eye bolt 33 is also provided in the upper end of the piston for the attachment of a cable to apply and remove the device from the overshot.

The operation of my invention is as follows:

With the device lowered into the overshot so that the piston 17 rests upon the slips 12 to dispose the guiding member G in its extreme position axially of the overshot and in its inactive position radially of the latter under the action of gravity, the overshot is lowered into the hole in which the drill pipe to be fished is located. The overshot is lowered to a point disposing the lower end of the member G at a level slightly above that at which the drill pipe is known to be broken off.

Circulating fluid is now pumped into the overshot casing so as to be forced through the pipe 25 and directed against the abutment 23, thus co-acting with the latter to swing the guiding member to its active position radially of the overshot as well as co-act with the piston to maintain the member in its extreme position axially of the overshot, all as shown in Figure 4.

The overshot is now lowered further in an effort to engage the lower extremity of the guiding member with the upper end of the broken off drill pipe, and should the member not be properly positioned circumferentially to engage the pipe, the overshot is raised slightly and then partially rotated to dispose the member in a new position circumferentially. This operation is repeated until the member engages the drill pipe upon which the beveled surface 26 of the member will operate to force the drill pipe towards the center of the hole until the member extends into the drill pipe with the shoulder 27 of the member resting upon the upper edge of the pipe as shown in Figure 4, after which circulation of the mud fluid is discontinued so as to relieve its pressure from the abutment 23 and from the piston.

The lowering movement of the overshot is now continued; and it will be clear that as the drill pipe supports the guiding member against further downward movement, the overshot will move downwardly relative to the member and piston as shown in Figure 5 to cause first the inclined surface 28 and then the inclined surface 29 of the member to be engaged by the inner wall of the overshot bowl 10 to thus co-act therewith in camming the member radially inward about the axis of the pin 14, thereby causing the member to move the upper end of the drill pipe towards the center of the hole so as to finally be centered sufficiently to enter the bowl. When the abutment 23 strikes the inner wall of the piston during this movement of the member by the overshot, the extension 20 flexes in order to permit further inward radial movement of the member sufficient for the pipe to become centered in the overshot.

The lowering movement of the overshot is continued until the drill pipe has entered the overshot casing a sufficient distance for the first coupling connecting the drill pipe sections to expand and pass the slips 12. Raising movement of the overshot is now initiated, causing the slips to engage beneath the coupling as shown in Figure 6 and exert a pulling force upon the drill pipe to raise the latter from the hole.

From the foregoing description it will be manifest that I have provided a device of simple and durable construction which in its association with an overshot, enables the latter to be readily applied to a drill pipe or casing, the upper end of which is eccentrically

disposed in the hole to such extent that the overshot along would be incapable of successfully fishing for the pipe, thereby materially increasing the range of use of the overshot and effecting a large saving in the drilling operation by preventing loss of the pipe and abandonment of the hole should it not be possible to drill by the pipe.

Although I have herein shown and described only one form of overshot embodying my invention, it is to be understood that various changes and modifications may be made therein without departing from the spirit of the invention and the spirit and scope of the appended claims.

I claim:

1. In combination, an overshot, a guiding member having a portion constructed to enter the upper end of a pipe in a bore hole, means for mounting the member in the overshot to project in advance of the latter and for movement from an inactive position to an active position wherein the projecting portion of the member is disposed beyond the diameter of the overshot bowl, and means for moving the member from inactive to active position.

2. In combination, an overshot, a guiding member adapted to engage a pipe, means for mounting the member in the overshot for movement longitudinally of the latter to normally project in advance of the overshot and for movement from an inactive position to an active position wherein the projecting portion of the member extends beyond the diameter of the overshot bowl, and means for moving the member from inactive to active position.

3. In combination, an overshot, a guiding member adapted to engage a pipe, means for mounting the member in the overshot for movement longitudinally of the latter to normally project in advance of the overshot, means for mounting the member on the first means for movement from an inactive position to an active position wherein the projecting portion of the member extends beyond the diameter of the overshot bowl, and means for moving the member from inactive to active position.

4. In combination, an overshot, a guiding member adapted to engage a pipe, means for mounting the member in the overshot for movement longitudinally of the latter to normally project in advance of the overshot, means for mounting the member on the first means for pivotal movement from an inactive position to an active position wherein the projecting portion of the member extends beyond the diameter of the overshot bowl, and means for moving the member from inactive to active position.

5. In combination, an overshot, a guiding member adapted to engage a pipe, means for mounting the member in the overshot for movement longitudinally of the latter to nor-

mally project in advance of the overshot, means for mounting the member on the first means for movement from an inactive position to an active position wherein the projecting portion of the member extends beyond the diameter of the overshot bowl, and means for moving the member from inactive to active position, the member having a surface engaged by the overshot for co-action therewith in moving a pipe towards the center of the hole during lowering movement of the overshot so as to enable the latter to move onto the pipe.

6. In combination, an overshot, a guiding member adapted to engage a pipe, means for mounting the member in the overshot for movement longitudinally of the latter to normally project in advance of the overshot, means for mounting the member on the first means for movement from an inactive position to an active position wherein the projecting portion of the member extends beyond the diameter of the overshot bowl, and means for moving the member from inactive to active position, the extremity of the projecting portion of the member being shaped to enter the end of a pipe and having a shoulder to abut the pipe end and limit movement of the member into the pipe.

7. In combination, an overshot, and means constructed to enter the upper end of a pipe disposed eccentrically in a bore hole, and co-acting with the overshot to guide the latter onto the pipe during lowering movement of the overshot in the hole.

8. A device of the character described comprising a guiding member, means for mounting the member in an overshot for movement axially thereof to normally project in advance of the overshot, and means pivotally mounting the member on the first means for movement radially with respect to the overshot.

9. A device of the character described comprising a guiding member, means for mounting the member in an overshot for movement axially thereof to normally project in advance of the overshot, means pivotally mounting the member on the first means for movement radially with respect to the overshot, and means for moving the member about the axis of the pivotal mounting to one extreme position.

10. In combination, an overshot, a guiding arm, means for mounting the arm in the overshot for movement axially thereof and co-acting with the slips of the overshot to normally support the arm with one extremity thereof projecting in advance of the overshot bowl, and means for mounting the arm on the first means for pivotal movement radially of the overshot to occupy inactive and active positions.

11. In combination, an overshot, a piston mounted in the overshot for movement axi-

ally thereof, a guiding arm pivotally mounted on the piston for movement radially with respect to the overshot, means for moving the piston to one extreme position wherein the arm projects in advance of the overshot bowl, and means for moving the arm about the axis of its pivotal mounting to an extreme position wherein the extremity of the projecting portion of the arm is disposed beyond the diameter of the overshot bowl.

12. In combination, an overshot, a guiding arm, a hollow piston on which the arm is pivoted, slidably mounted in the overshot for movement axially thereof and movable under the action of fluid pressure to one extreme position wherein the arm projects in advance of the overshot bowl, and fluid pressure responsive means for moving the arm about the axis of its pivotal mounting on the piston to one extreme position.

13. In combination, an overshot, a guiding arm, a hollow piston on which the arm is pivoted, slidably mounted in the overshot for movement axially thereof and movable under the action of fluid pressure to one extreme position wherein the arm projects in advance of the overshot bowl, the arm having an extension disposed in the piston, an abutment on the extension, and a pipe carried by the piston and disposed to direct fluid under pressure against the abutment to move the arm about the axis of its pivotal mounting on the piston to one extreme position.

14. The combination as embodied in claim 13 wherein the piston is provided with ports and a check valve through which fluid is adapted to pass from the piston.

15. The combination as embodied in claim 13 wherein the extension of the arm is flexible for the purpose described.

16. In combination, an overshot, a guiding member, means for mounting the member in the overshot for movement axially and radially of the latter, and means for moving the member axially and radially to a position wherein the member projects in advance of the overshot bowl with the extremity of the projecting portion of the member disposed beyond the diameter of the overshot bowl.

17. In combination, an overshot, a guiding member, means for mounting the member in the overshot for movement axially and radially of the latter, and means for moving the member axially and radially to a position wherein the member projects in advance of the overshot bowl with the extremity of the projecting portion of the member disposed beyond the diameter of the overshot bowl, the member having a surface with which the overshot co-acts to move the member radially inward from said position in response to axial movement of the overshot towards said extremity of the member.

18. An overshot having a guiding member projecting in advance and beyond the diameter of the overshot bowl constructed to enter the upper end of a pipe disposed eccentrically in a bore hole, and means whereby lowering movement of the overshot in the hole will cause the member to enter and move the pipe towards the center of the hole to a position wherein it will enter the overshot as the lowering operation proceeds.

19. An overshot having a guiding member positioned to enter the upper end of a pipe disposed eccentrically in a bore hole, and means on the member and overshot co-acting in response to lowering movement of the latter, to move the pipe towards the center of the hole sufficiently for the pipe to enter the overshot.

20. In combination, an overshot, a guiding member having a portion constructed to enter the upper end of a pipe in a bore hole, means for mounting the member in the overshot to project in advance of the latter and for movement from an inactive position to an active position wherein the projecting portion of the member is disposed beyond the diameter of the overshot bowl, means for moving the member from inactive to active position, and means for limiting the extent to which the member can enter the pipe.

21. In combination, an overshot, a guiding member having a portion constructed to enter the upper end of a pipe in a bore hole, means for mounting the member in the overshot to project in advance of the latter and for movement from an inactive position to an active position wherein the projecting portion of the member is disposed beyond the diameter of the overshot bowl, and means for moving the member from inactive to active position, said portion of the member having a shoulder adapted to abut the pipe ends to limit movement of the member into the pipe.

22. An overshot having a guiding member positioned to enter the upper end of a pipe disposed eccentrically in a bore hole, means for limiting the extent to which the member can enter the pipe, and means on the member and overshot co-acting in response to lowering movement of the latter, to move the pipe towards the center of the hole sufficiently for the pipe to enter the overshot.

BRUNO J. CLOUSE.
